[57] **CLAIM**

The ornamental design for a finger-mounted light, as shown and described.

DESCRIPTION

FIG. 1 is a top, front perspective view of a finger-mounted light showing my new design, the hand being shown in broken lines for illustrative purposes;

FIG. 2 is a top plan view thereof;

FIG. 3 is a side elevational view thereof;

FIG. 4 is a front elevational view thereof;

FIG. 5 is a rear elevational view thereof;

FIG. 6 is a bottom plan view thereof;

FIG. 7 is an opposite side elevational view thereof.
